Primary Examiner — Jennifer Rivard(74) Attorney, Agent, or Firm — Panasonic IP Management; Kerry S. Culpepper(57) CLAIM

We claim the ornamental design for an electric epilator device, as shown and described.

DESCRIPTION

FIG. 1 is a front perspective view of an electric epilator device of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines illustrate portions of the electric epilator device and form no part of the claimed design.
